(57) **CLAIM**

The ornamental design for a reduced pressure treatment apparatus, as shown and described.

DESCRIPTION

FIG. 1 shows an isometric, first side view of a reduced pressure treatment apparatus according to an illustrative embodiment;

FIG. 2 shows an isometric, rear view of the reduced pressure treatment apparatus of FIG. 1;

FIG. 3 shows a front view of the reduced pressure treatment apparatus of FIG. 1;

FIG. 4 shows a rear view of the reduced pressure treatment apparatus of FIG. 1;

FIG. 5 shows the first side view of the reduced pressure treatment apparatus of FIG. 1;

FIG. 6 shows a second side view of the reduced pressure treatment apparatus of FIG. 1;

FIG. 7 shows a top view of the reduced pressure treatment apparatus of FIG. 1; and,

FIG. 8 shows a bottom view of the reduced pressure treatment apparatus of FIG. 1.

The broken lines illustrated in the drawings are for illustrative purposes only and form no part of the claimed design.
